UNITED STATES PATENT OFFICE

160,605

COMBINATION BAR UTENSIL

George S. Iskyan, Jackson Heights, N. Y.

Application January 17, 1950, Serial No. 7,300

Term of patent 7 years

(Cl. D44—29)

To all whom it may concern:

Be it known that I, George S. Iskyan, a citizen of the United States and a resident of Jackson Heights, county of Queens, State of New York, have invented a new, original, and ornamental Design for a Combination Bar Utensil, of which the following is a specification, reference being had to the accompanying drawing, forming part thereof.

In the drawing:

Fig. 1 is a side view of a combination bar utensil embodying my design; and

Fig. 2 is a side view thereof, with the cork-screw cover thereof detached.

I claim:

The ornamental design for a combination bar utensil, as shown.

GEORGE S. ISKYAN.
